Primary Examiner — Sandra Snapp*Assistant Examiner* — Ieisha N Price(74) *Attorney, Agent, or Firm* — Banner & Witcoff, Ltd.(57) **CLAIM**

The ornamental design for connector, as shown and described.

DESCRIPTION

FIG. 1 is a front perspective view of a connector showing my new design showing the connector in an assembled state;
FIG. 2 is a top plan view thereof;
FIG. 3 is a right side view thereof;
FIG. 4 is an exploded rear perspective view thereof showing the circular spring-biases in a non-compressed position;
FIG. 5 is a front perspective view of FIG. 4;
FIG. 6 is a top view of FIG. 4;
FIG. 7 is an exploded top view thereof showing the circular spring-biases in a compressed position;
FIG. 8 is a left side view of FIG. 4, the right side view being a mirror image thereof; and,
FIG. 9 is a left side view of FIG. 7.
The broken lines in the drawings illustrate portions of the connector which form no part of the claimed design.
